UNITED STATES PATENT OFFICE.

JOHN STANLEY MORGAN, OF LONDON, ENGLAND, ASSIGNOR TO THERMAL INDUSTRIAL AND CHEMICAL (T. I. C.) RESEARCH COMPANY LIMITED, OF LONDON, ENGLAND.

HEAT TREATMENT OF SUBSTANCES BY MEANS OF MOLTEN METAL.

Application filed November 20, 1922, Serial No. 602,182, and in Great Britain January 4, 1922.

In processes of subjecting materials to heat treatment by means of molten metal or alloy it is generally necessary to avoid removing the metal from the bath together with the treated material. When the material is in comparatively large pieces there is no particularly difficulty in fulfilling this necessity; but when powdered, granular, fibrous or other finely-divided material has 10 to be removed it is difficult to avoid the presence of globules of metal in the discharged material.

I have found that it is possible to carry finely-divided material from the surface of 15 molten metal in an upwardly moving current of elastic fluid, and that the material carried from the surface in this manner is free, or substantially free, from molten metal. It is sufficient to create or maintain 20 a difference between elastic fluid pressure within the apparatus and that without it, so as to cause a flow of elastic fluid outwardly from the vessel; by causing the current of elastic fluid to pass over the material to be 25 removed, and to take an upward course, the material may be entrained in the current of elastic fluid and removed from the surface of the molten metal. The elastic fluid leaving the still, and the material carried in suspension, may then be separated in any convenient manner.

Apparatus for carrying out the foregoing method comprises a still which contains molten metal, and is gas-tight, except for 35 the means of exit afforded by a discharge pipe arranged to extend upwardly, and with its lower end in close proximity to the surface of the molten metal. Treated material is caused to collect on the surface of the 40 molten metal beneath the lower end of the discharge chute, and is carried through the chute, and discharged at the upper end thereof, by means of a current of elastic fluid leaving the apparatus by way of the 45 discharge chute.

When the heat treatment is a process of destructive distillation or the like in which elastic fluid products are evolved, the pressure exerted by these products may be used 50 for expelling the residual product of the distillation from the vessel which serves as the retort and contains the molten metal. For instance, when a material like saw-dust is being carbonized it may be so conveyed 55 over or through the molten metal that the

carbonized product collects beneath a nozzle which is fixed clear of the molten metal surface and is attached to a pipe which extends to the outside of the vessel. In such case the pressure of the gas and vapour evolved from the fresh sawdust which is being carbonized will carry the carbonized material through the pipe which may deliver it to a separator where it is removed from the gas and vapour, preferably before 60 any condensation occurs, and any particles of metal that may be mixed with the carbonized material which remains in the still will be absorbed again in the molten bath. 65

When the heat treatment is one that does 70 not evolve elastic fluid, or evolves too little to create the required pressure, steam or other suitable elastic fluid may be introduced into or generated in the vessel. This is often desirable in order to assist the distillation. 75

In order to take advantage of this method of discharge it is often desirable to provide for the crushing of the residual product inside the vessel before the expulsion of the 80 product. It is possible by this means to introduce the material in larger pieces, and to treat materials which cake together during the course of the heat treatment or distillation, the crushing means serving to reduce large or caked pieces to particles of 85 such size that no difficulty is experienced in their discharge by the method of the invention.

The accompanying drawings illustrate an 90 apparatus which operates in accordance with the invention, Fig. 1 being a longitudinal vertical section and Fig. 2 a cross section on line A—B of Fig. 1.

The material, such as wood chips which 95 are to be destructively distilled, is fed through a gas-tight feeding device (not shown) down a chute *a* into the tank *b* containing molten lead *c*. It is caught by the blades *d* of a drum *e* revolving in the direction indicated by the arrow and is thereby carried through the metal to return again to the surface in front of the rollers *f* which extend across the tank. The lower roller is driven, so that, as the material is piled 100 by action of the drum against the rollers, it is caught between them and passes on in a suitably crushed condition. 105

The gas-tight cover of the tank has a man-hole suitably sealed by a cover *g* having 110

handles *h*. The tank is divided into compartments above the surface of the molten metal by a transverse vertical partition *i* in which is an opening to receive the curved 5 upper edge *k* of a plate *l* shaped like a hood and having an upward extension *m* which slides against the partition *i* to make a substantially gas-tight joint. The plate *l* is fixed to a screw spindle *n* working in a nut 10 *o*, so that by rotating the latter the plate can be raised or lowered. The plate *l* extends across the tank, and as the material is pushed forward by action of the rollers *f*, it passes beneath the plate. The opening 15 afforded by this hood-shaped plate, however, is the sole passage for the elastic fluid produced by the destructive distillation, and in escaping through this opening the elastic fluid carries with it the charred material. 20 The latter is deflected by the curved edge *k* into the chute *p* whence it is removed by a gas-tight discharging device (not shown), while the elastic fluid escapes by the pipe *q*. The distance of the lower edge of the plate 25 *l* from the surface of the lead is so adjusted as to ensure that the escaping elastic fluid has a velocity sufficient to raise the material without lifting up to the discharge opening any globules of metal from the heated metal 30 bath. Globules of lead which may ascend towards the opening in the partition *i*, together with the material to be removed, fall back into the lead bath before they arrive at the opening. 35 The bearings of the rollers *f* are mounted in arms *r*, one on each side of the tank, which can be fixed at an angle suitable for the size of material under treatment, by pins engaging in perforations in the arms and 40 in corresponding sectors *s*.

When the angle of inclination to the horizontal of the plane containing the axes of the rollers *f* is small, the effective "pocket" formed is suitable for the reception of 45 coarser particles, which are then carried between the rollers by the positive rotation of the lower roller. Under these conditions, however, material in a finer state of subdivision tends to heap up and pass over the upper roller, and in the case of such 50 material this tendency is diminished by increasing the angle of inclination to the horizontal of the arms *r*.

The apparatus described is suitable for 55 treating materials which, during this treatment, evolve sufficient elastic fluid for carrying the treated material out of the still. If it is required to treat materials which do not evolve elastic fluid, or evolve too little 60 to produce the contemplated effect, the apparatus may easily be adapted for this purpose by providing at any suitable place an inlet pipe (not shown) for the introduction of steam or other elastic fluid or a material 65 which will yield an elastic fluid in the still.

Having thus described the nature of the said invention and the best means I know of carrying the same into practical effect, I claim:—

1. In processes of subjecting to heat treatment, by contact with a bath of molten metal, materials which yield by the treatment a solid residue of lower specific gravity than the molten metal, the method of removing the solid residue from the surface 70 of the molten metal in a condition substantially free from metal, which consists in causing the residue to accumulate on the surface of the molten metal beneath an upwardly directed duct and to be entrained in 75 a stream of elastic fluid moving upwardly through the duct.

2. In processes of subjecting to heat treatment, by contact with a bath of molten metal, materials which yield by the treatment 80 elastic fluid and a solid residue of lower specific gravity than the molten metal, the method of removing the solid residue from the surface of the molten metal in a condition substantially free from metal 85 which consists in causing the residue to accumulate on the surface of the molten metal beneath an upwardly directed duct and to be entrained in a stream of the elastic fluid product of the treatment moving 90 upwardly through the duct.

3. In processes of carbonizing, by contact with a bath of molten metal, carbonizable materials which yield on carbonization 95 elastic fluid and a solid residue of lower 100 specific gravity than the molten metal, the method of removing the solid residue from the surface of the molten metal in a condition substantially free from metal which 105 consists in causing the residue to accumulate on the surface of the molten metal beneath an upwardly directed duct and to be entrained in a stream of the elastic fluid product of the carbonization moving 110 upwardly through the duct.

4. Apparatus for subjecting materials to 115 heat treatment by means of molten metal, comprising a still to contain molten metal, and an upwardly directed discharge chute forming the sole normal means of exit for elastic 120 fluid from the still and having its lower end arranged to be in close proximity to and above a part of the surface of the molten metal, and adjustable with respect to the distance of its lower end from the surface of the molten metal.

5. Apparatus for subjecting materials to 125 heat treatment by means of molten metal, comprising a still to contain molten metal, a gas-tight feeding chute adapted to feed the material to be treated to the molten metal, an upwardly directed discharge chute forming the sole normal means of exit for elastic fluid from the still and having its lower end arranged to be in close proximity to and 130

above a part of the surface of the molten metal, and adjustable with respect to the distance of its lower end from the surface of the molten metal, and means for causing the material to be treated to travel in contact with the molten metal from the feeding chute to the discharge chute.

6. Apparatus for subjecting materials to heat treatment by means of molten metal
 10 comprising a still to contain molten metal, a gas-tight feeding chute adapted to feed the material to be treated to the molten metal, an upwardly directed discharge chute forming the sole normal means of exit for elastic fluid
 15 from the still and having its lower end arranged to be in close proximity to and above a part of the surface of the molten metal, means for causing the material to be treated to travel in contact with the molten metal from
 20 the feeding chute to the discharge chute, and rollers situated intermediately of the feeding chute and the discharge chute and adapted to crush the treated material before it enters the discharge chute.
- 25 7. Apparatus for subjecting materials to heat treatment by means of molten metal, comprising a still to contain molten metal, a gas-tight feeding chute adapted to feed the material to be treated to the molten metal, an
 30 upwardly directed discharge chute forming the sole normal means of exit for elastic fluid from the still and having its lower end arranged to be in close proximity to and above a part of the surface of the molten metal, and
 35 adjustable with respect to the distance of its lower end from the surface of the molten metal, means for causing the material to be treated to travel in contact with the molten metal from the feeding chute to the discharge chute, and rollers situated intermediately of the feeding chute and the discharge chute and adapted to crush the treated material before it enters the discharge chute.
- 40 8. Apparatus for subjecting materials to heat treatment by means of molten metal, comprising a still to contain molten metal, a gas-tight feeding chute adapted to feed the material to be treated to the molten metal, an upwardly directed discharge chute forming
 45 the sole normal means of exit for elastic fluid

from the still and having its lower end arranged to be in close proximity to and above a part of the surface of the molten metal and adjustable with respect to the distance of its lower end from the surface of the molten metal, means for causing the material to be treated to travel in contact with the molten metal from the feeding chute to the discharge chute, rollers situated intermediately of the feeding chute and the discharge chute and
 55 adapted to crush the treated material before it enters the discharge chute, and a pipe located exterior of the discharge chute and communicating therewith for drawing off the elastic fluid escaping from the still with the
 60 treated material.

9. Apparatus for subjecting materials to heat treatment by means of molten metal, comprising a still to contain molten metal, a gas-tight lid to said still, a gas-tight chute
 70 adapted to feed the material to be treated to the molten metal, an upwardly directed discharge chute extending through a wall of said still and forming the sole normal means of exit for elastic fluid from the said still, said discharge chute having its lower end arranged to be in close proximity to and above a part of the surface of the molten metal, means for adjusting the distance of the mouth of said discharge chute from the surface of the molten metal, a drum situated near to the feeding chute and intermediately of the feeding chute and the discharge chute, said drum being partially immersed in the molten metal and adapted to be rotated on a
 75 horizontal axis, vanes on the said drum, rollers having their axes parallel to each other, said rollers being adjustable in respect of the angle of inclination to the horizontal of the plane containing their axes and being situated intermediately of the feeding chute and the discharge chute and adapted to crush the treated material before it enters the discharge chute and a pipe located exterior of the discharge chute and communicating therewith for drawing off elastic fluids escaping from the still with the treated material.

In testimony whereof I have signed my name to this specification.

JOHN STANLEY MORGAN.
